UNITED STATES PATENT OFFICE.

MICHAEL TENYÁK, OF AMHERST, OHIO.

BEEHIVE.

1,144,878.

Specification of Letters Patent. Patented June 29, 1915.

Application filed March 10, 1915. Serial No. 13,506.

To all whom it may concern:

Be it known that I, MICHAEL TENYÁK, a subject of the King of Hungary, residing at Amherst, in the county of Lorain and State of Ohio, have invented certain new and useful Improvements in Beehives, of which the following is a specification.

This invention relates to certain new and useful improvements in bee-hives.

10 The primary object of this invention is to provide a bee-hive or apiary designed for the accommodation of a plurality of frame-carrying racks, the frames being adapted for holding honey boxes or comb supports of a 15 pre-determined commercial size and the said racks being arranged one above the other and slidably removable through the hinged doors of the hive casing.

20 A further object is to provide a bee-hive arranged in two stories for the accommodation of the comb holders, the upper story being closable when desired for employing only the lower story for the operations of the bees.

25 A still further object is to provide a bee-hive having a casing which is well ventilated and is adapted to hold honey-receiving comb portions, the casing having a hinged transparent door for allowing visual access to 30 the interior of the hive during the honey making operation.

With these general objects in view and others that will appear as the nature of the invention is better understood, the same consists in the novel combination and arrangement of parts hereinafter more fully described, illustrated in the accompanying drawings, and pointed out in the appended claims.

40 In the drawings forming a part of this application and in which like designating characters refer to corresponding parts throughout the several views:—Figure 1 is a front elevation of the hive with the upper 45 door in its open position and partially broken away. Fig. 2 is a rear elevation of the device. Fig. 3 is a central vertical longitudinal sectional view thereof. Fig. 4 is a horizontal sectional view taken upon line 50 IV—IV of Fig. 3. Fig. 5 is a perspective view of the ventilating slide removed. Fig. 6 is a perspective detail view showing the communicating passage between the upper and lower compartments of the casing and 55 slidable closure therefor. Fig. 7 is a per-

spective view of the sliding closure removed from the partition. Fig. 8 is a perspective view of an end portion of one of the removable racks employed within the casing, and, Fig. 9 is a perspective view of one of 60 the honey-comb mounting frames provided for the said racks.

The present invention contemplates the provision of a casing 10 having a gabled roof 11 and provided with upper and lower compartments 12 and 13 respectively, each of which is open at the front of the casing and is provided with a hinged closure and door 14. A central horizontal partition 15 is provided within the casing between the 70 said two compartments while similar entrance openings 16 are provided in the rear wall 17 of the casing for allowing the bees to have free passage to and from the said compartments. The entrance 16 of the 75 upper compartment 12 is provided with a closure slide 18 having ventilating perforations 19 therethrough by means of the handle 20 secured thereto.

A glass door 21 is hingedly mounted at 80 the open side of the upper compartment 12 rearwardly of the solid closure door 14 thereof and by this means the interior of the upper compartment may be readily seen upon opening the outer door 14. 85

The partition 15 is provided with a vertical passage 22 therethrough adapted to be opened and closed by the closure member 23 which is slidably mounted in a central transverse passage or guide channel 24 of the 90 said partition 15, the said closure having a stop pin 25 projecting therefrom into the passage 22 and it will thus be evident that the said closure 23 may be slidably positioned inwardly for closing the passage 22 95 as shown in Figs. 3 and 4 or the same may be withdrawn outwardly as far as permitted by the said pin 25, and thus opening the said passage 22 as illustrated in Fig. 6.

The outer end of the closure 23 is provided with spaced triangular lugs 31 and by means of which the said closure may be engaged for slidably moving the same for opening and closing the passage 22. When the said closure is positioned in its closed relation as shown in Fig. 4, it will be seen that the lugs 31 lie entirely within the partition-receiving opening 24, so that the fingers of the operator may be inserted between the said lugs for engaging the opposite inner 110

edges thereof for the purpose of outwardly moving the said closure.

A separate rack 26 is provided for each of the two compartments of the casing and these racks are slidably positioned within the compartments by being inserted through the open front portions thereof when the doors 14 are open while leaf springs 27 are mounted within each compartment and upon the rear casing wall 17 and adapted to be contacted and slightly elevated by the entering racks, which springs thereby slightly retain the racks in position when slid to the limit of their inward movements within the compartments, and against the rear stops 28 provided therein. These racks 26 are provided upon the inner faces of their upper and lower sides with alining spaced lugs 29 which are adapted to slidably receive therebetween as many of the frames 30 as the racks are designed to accommodate.

It will be understood that in the employment of the present bee-hive, the artificially formed comb chambers furnished in sections and adapted to be filled by the bees are employed as is customary at the present time in the apiary business. A plurality of comb portions are arranged in the frame 30 and each of the same may be designed to furnish a desirable quantity or weight of honey, such as a one pound, two pound, or three pound box. The frames 30 being thus filled with the comb boxes are slidably positioned within the racks 26 and the racks are slidably placed within the compartments 12 and 13 and the front doors of the casing are closed. The bees gain access to the comb within the lower compartment 13 through the rear opening 12 of the casing and are thus enabled to fill the comb with honey. When desired to also use the upper compartment 12, the closure 23 is slid outwardly to its open position as shown in Fig. 6 and the bees may freely pass through the partition opening 22 while they also have free access to the upper compartment through the opening 16 in the casing rear wall. The frames 30 may be separately removed if desired when the comb contained therein is filled with honey or the racks 26 may be manually removed with the frames mounted therein. When a frame has been removed, the separate boxes of honey are taken therefrom and are ready for commercial use as honey in the comb while of course, the honey may be extracted from the comb before selling the same if desired in any of the well-known manners.

It will thus be seen that a serviceable hive is provided in which the quantities of honey convenient for use will result from the work of the bees while well-ventilated and suitable compartments are provided in which the bees are housed for the performance of their work.

While the forms of the invention herein shown and described are what are believed to be the preferred embodiments thereof, it is nevertheless to be understood that minor changes may be made without departing from the spirit and scope of the invention as set forth in the appended claims.

What I claim as new is:

1. A bee-hive comprising a casing having a transverse partition formed with a passage therethrough and adjacent the rear side thereof, the said partition being further provided with a forwardly open slide channel communicating with the said passage, the said partition further forming honey-comb receiving compartments, a closure slidably mounted in said channel and having spaced hand-engaging triangular shaped lugs upon its outer end, means carried by said closure member adapted to engage a side wall of said passage to limit the outward movement of said closure member, hinged closure doors for each compartment, the upper closure door constituting a closure for the outer open end of said channel, the said lugs being positioned within the outer end of the said channel when the closure is in its closed position transversely of the said passage.

2. A bee-hive comprising a casing having upper and lower bee inlets through its rear wall, a perforated slide shiftably mounted adjacent the said upper inlet, a transverse partition within the said casing having a transverse passage therethrough, the said partition dividing the casing into an upper and a lower compartment, a slideable closure for the said passage carried by the said partition, means carried by said closure member adapted to engage a side wall of said passage to limit the outward movement of said closure member, a hinged closure door for the lower compartment and a glass hinged closure door for the upper compartment, and honey-comb mounting racks slidably positioned within the said compartments.

3. A bee-hive comprising a casing having upper and lower compartments, leaf springs mounted at the rear of said compartments, racks slidably mounted within said compartments and having their inner ends resiliently engaged beneath the said springs, upper and lower series of spaced lugs carried by the said racks in longitudinal alinement with each other, and honey-comb mounting frames slidably positioned in the said racks between the said lugs thereof.

4. In combination with a bee-hive including a casing and a partition wall having a transverse opening therein, there being a channel formed in said partition and communicating with said opening, a slide closure plate mounted in said channel and adapted to be moved to position to close the partition opening, and means carried by said

closure plate adapted to engage a side wall of said opening to limit the outward movement of the closure plate.

5. A bee-hive including a casing, a partition dividing the casing into independent compartments, guide tracks arranged in each compartment, racks slidably mounted in each compartment and limited in their inward movement by said guides, and resilient members carried by said casing adapted to engage said racks to retain the same in position within the casing.

6. A bee-hive including a casing, guiding

members within said casing, honey-comb racks associated with said guides, spaced lugs carried by said racks adapted for positioning the honey-combs therein, and means carried by said casing and associated with said racks whereby the racks are retained in position.

In testimony whereof I affix my signature in presence of two witnesses.

MICHAEL TENYÁK.
